(57) **CLAIM**

The ornamental design for a chair handle with hook, as shown and described.

DESCRIPTION

FIG. 1 is a perspective view of a chair handle with hook in accordance with the present invention;

FIG. 2 is a rear view of the chair handle with hook of FIG. 1;

FIG. 3 is a front view of the chair handle with hook of FIGS. 1 and 2;

FIG. 4 is a side view of the chair handle with hook of FIGS. 1-3;

FIG. 5 is an opposite side view of the chair handle with hook of FIGS. 1-4;

FIG. 6 is a top view of the chair handle with hook of FIGS. 1-5; and,

FIG. 7 is a bottom view of the chair handle with hook of FIGS. 1-6.

The broken lines shown in the Figures are for environmental purposes only and form no part of the claimed design.
